UNITED STATES PATENT OFFICE.

CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPE-WRITING MACHINE.

999,942.

Specification of Letters Patent. Patented Aug. 8, 1911.

Application filed April 22, 1909. Serial No. 491,459.

To all whom it may concern:

Be it known that I, CLIO B. YAW, citizen of the United States, and resident of Arlington, in the county of Hudson and State of New Jersey, have invented certain new and useful Improvements in Type-Writing Machines, of which the following is a specification.

My invention relates especially to what is commonly termed tally strip mechanism for typewriting machines, and its object, generally stated, is to provide improved devices of the class specified.

To the above and other ends, my invention consists in the features of construction, combinations of devices and arrangements of parts hereinafter described and particularly pointed out in the claims.

The accompanying drawings show one form of my invention as applied to the platen frame or carrier of a No. 11 Remington typewriting machine.

Figure 1 is a fragmentary top plan view of the platen and platen frame or carrier with my invention applied thereto. Fig. 2 is a fragmentary front elevation of the right-hand end portion of the same. Fig. 3 is a vertical sectional view taken transversely of the platen and looking toward the right. Fig. 4 is a view corresponding to Fig. 3 but showing some of the parts in different relations, other parts being omitted. Fig. 5 is a fragmentary detail end view of the tally strip line spacing devices. Fig. 6 is a fragmentary sectional view taken on planes represented by the broken line α in Fig. 3 and looking in the direction of the arrow at said line. Fig. 7 is a transverse sectional view of a platen showing a modified construction of inking device for the tally strip. Fig. 8 is a fragmentary face view of the platen shown in Fig. 7, parts being broken away.

The platen frame or carrier of the No. 11 Remington machine is mounted on a carriage (not shown) and is composed of a rear bar 1, side or end bars 2 and 3 and a cross bar 4 connecting the end bars below the platen 5, the axle 6 whereof bears in the said end bars (Figs. 1 to 4). At its right-hand end, the platen is provided with the usual line spacing ratchet wheel 7, with which a roller detent 8 cooperates. A line spacing pawl 9 is mounted on an arm 10 pivoted to the platen axle 6. The pawl 9 is caused to engage with the teeth of the ratchet wheel and

turn the platen by hand controlled line spacing devices including a forwardly extending link 11. Angular arms 12 are secured to the cross bar 4 and provide bearings at their upper ends for a rock shaft 13, said rock shaft also bearing in the end bars 2 and 3. The rock shaft supports the rear end of a paper apron 14 that extends forward around the under side of the platen and is formed with openings through which the sections composing the front and rear feed rollers 15 and 16 are protrusive to contact with the platen or the paper thereon. The feed roller shafts are supported at opposite ends of arms 17 pivoted at 18 on three-armed members 19 supported on a rod 20 secured to the angular arms 12. Each member 19 has an upwardly extending arm 19^a which is engageable by a finger 21 secured to the rock shaft 13. Said members 19 also have downward extending arms 19^b connected to draw springs 19^c. The rock shaft 13 near its left-hand end is provided with an arm or finger piece 22 by which it may be turned rearward, a spring 23^x restoring said rock shaft and connected parts to normal position when the arm 22 is released. When the rock shaft is turned rearward, the fingers 21 operate on the members 19 to release the feed rollers 15 and 16, the latter moving from the position shown in Fig. 3 to that shown in Fig. 4. The parts thus far referred to are common to the No. 11 Remington machine and need not be further described.

The tally strip devices to which my present invention more especially relates are supported on a frame or bracket 23 provided with two downwardly extending branches or fingers 23^a which receive screws 24 whereby the bracket is detachably secured to the end bar 3 (Figs. 1 to 4). From its points of attachment to the end bar the supporting frame 23 extends upward and forward over the top of the platen and inward or leftward toward the middle thereof, so that the tally strip rolls which are supported at the upper end portion of said frame or bracket are disposed above the platen and somewhat to the left of its right-hand end. These tally strip rolls are shown in detail in Fig. 6. The delivery roll 25, which is the lower roll and is arranged somewhat to the rear of the receiving roll, is journaled on a rod or arm 26 which is detachably secured by a nut 27 to the bracket 23 and projects hori-

zontally inward therefrom. A stop or cross arm 28 is suitably secured to the left-hand end of the rod 26 and the roll 25 is pressed against the stop by a coiled spring 29 surrounding the rod 26 at the right of the roll, said coiled spring acting against a washer 30 which contacts with the end of the roll. The construction is such that the washer 30 and cross arm 28 exert sufficient friction 10 against the ends of the roll to prevent it from rotating too freely and unwinding the tally strip to an unnecessary extent. The roll or core piece 25 is shown solid and may be of wood, but of course may be otherwise 15 constructed and of different material if preferred. The upper or receiving roll for the tally strip is shown as comprising a hollow tubular body 31 having end pieces or plugs 32 and 33 suitably secured in its ends. 20 These plugs are perforated to receive a rod or arm 34 which projects inward parallel to the rod 26 and is detachably secured to the bracket 23 by a nut 35. A nut 36 at the inner end of the rod 34 prevents accidental detachment of the receiving roll and maintains said roll in contiguity to a flange 34^a on the rod 34. A ratchet wheel 37 is preferably formed integral with the end plug 33, said ratchet wheel coöperating with 25 devices hereafter to be described for communicating step-by-step line spacing movements to the tally strip. The end plug 32 is preferably knurled on its periphery outside the tube 31 so as to provide a convenient 30 means for turning the receiving roll by hand. The tally strip 38 is wound on the delivery roll or core piece 25 and, as shown in Figs. 3 and 4, is led down from the back of the roll 25 around the platen and upward 35 at the front of the receiving roll to which the free end of the tally strip is or may be attached by a finger or clip 39 which is suitably secured to the tubular part 31 by a rivet 40 and extends lengthwise of said tubular portion from which it is only slightly separated. An arm or rod 41 is detachably secured by a nut 41^a to an extension 23^b of the bracket 23. Said rod 41, which is shown 40 as hexagonal, extends inward parallel with and below the rod 26 and has a reduced cylindrical portion 41^b which provides a bearing for a combined support and guide in the form of a flanged spool 42. This spool is prevented from being accidentally detached 45 from its bearing by a nut 43 and provides a support for an endless transfer band 44 which is or may be an ink ribbon. The endless inking band is hung on the spool 42 and extends downwardly therefrom around the platen 50 which it partially surrounds inside the tally strip 38. The tally strip and the inking band are preferably of substantially the same width, and the tally strip overlies the inking band which is interposed between 55 said tally strip and the surface of the platen.

Preferably the platen sheath is cut away to provide a shallow circumferential groove or depression 45 which receives the inking band and tally strip so that where these elements hug the platen they do not project beyond the surface thereof. This construction enables the wide work sheet or invoice (not shown) to extend widthwise through substantially the entire length of the platen and over the tally strip and inking band without being caused by the latter elements to bulge at the place where said invoice passes over them. It also enables the invoice or bill sheet to be line spaced by the regular line spacing devices without line spacing or otherwise affecting the tally strip. When, on the other hand, the tally strip is line spaced or fed lengthwise it is not impeded by the invoice sheet which overlies it. A spring arm or detent 46 is secured by a screw 47 at the rear of the arm 41 and extending upwardly therefrom engages the teeth of the ratchet wheel 37, which ratchet wheel, it will be recalled, is integral with the tally strip receiving roll. The detent 46 and 85 ratchet wheel 37 coöperate to maintain or hold the tally strip receiving roll in positions in which it may be adjusted. The delivery tally strip roll, it will be recalled, is frictionally controlled. The consequence 90 is that slack in the tally strip between the rolls is prevented and the tally strip is always taut. When the tally strip is advanced either forward or backward it slips or slides over the band 44 which is not advanced by these movements of the tally strip. The engagement of the inking strip or band 44 with the depressed face of the platen is, however, sufficiently tight to cause a feeding of the inking band when the 100 platen is turned for line spacing or other purposes. Because of this frictional feeding of the inking band by the platen during line spacing movements thereof, it will be understood that different portions of the 105 inking band will receive the impact of the printing types for the different numbers written on the invoice and tally strip.

Means are preferably provided for automatically advancing or line spacing the tally strip, these means in the present instance being actuated by the operation of the releasing arm 22. Said means comprise an arm 48 which is pivotally mounted on the rod 34 at the right of the flange 34^a against which it is maintained by a washer 49. Pivoted on a screw 50 carried by the free end of the arm 48 is a pawl member 51 having a hub 52 which bears on the screw 50. The member 51 is provided with a pawl tooth 53 which is normally maintained in engagement with one or another of the teeth of the ratchet wheel 37 by a coiled spring 54, said spring surrounding the hub 52 and having one of its ends 115 secured to the screw 50.

arm 48 and the other of its ends secured to the pawl member 51. At the side of its pivot opposite the pawl tooth 53, said pawl member 51 is provided with a laterally disposed finger piece 55. By depressing this finger piece the pawl tooth may be disengaged from the ratchet wheel 37, permitting backward and turning movements to be given to the tally strip receiving roll by hand. An actuating link 56 has its upper end pivotally connected by a shouldered screw 57 to the arm 48 and extends downward and rearward behind the platen, the lower end of said link 56 being pivotally connected at 58 to a crank arm 59. Said crank arm extends upward and rearward from the rock shaft 13 to which rock shaft it is suitably secured in fixed relation. The rock shaft restoring spring 23 normally maintains the crank arm 59, link 56 and arm 48 in the positions shown in Figs. 3 and 4. When at the completion of the writing of an invoice, the release arm 22 is pushed rearward, turning the shaft 13 rearward and releasing the feed rolls so that the invoice may be readily withdrawn, an automatic advance of or line spacing of the tally strip will be effected. The rearward turning of the rock shaft 13 turns the crank arm 59 which pulls the link 56 downward, thereby swinging the arm 48 and causing the pawl member 51 to advance the ratchet wheel 37 and tally strip receiving roll a single space.

The normal positions of the feed rolls, the release arm 22 and connected parts, including the crank arm 59, link 56 and pawl member 51, are shown in Fig. 3, while the released position of the feed rolls and corresponding actuated positions of the crank arm, link and pawl member are shown in Fig. 4. When the release arm 22 is freed, the parts will be restored to the Fig. 3 position by the associate restoring springs.

It will be understood that during the writing of the body of the invoice and during the line spacing thereof, the tally strip will not be written upon, nor will its relation with the printing point be changed. The writing of the body of the invoice, of course, is effected through the usual inking ribbon (not shown). When the total or other memoranda is to be printed on the tally strip, the depressed portion 45 of the platen is brought opposite the printing point and thereafter when the printing instrumentalities are operated a double imprint of each will take place. The invoice will be printed on as usual through the main or ordinary ink ribbon while the back of the tally strip will receive imprints from the underlying auxiliary inking ribbon 44. The tally strip employed is of tissue or other thin material so that the imprints made on the back thereof may easily be read through the tally strip from the front. When the inking band 44

has been exhausted it may readily be replaced by a fresh inking band.

In Figs. 7 and 8 I have shown another form of inking device for the tally strip, which form may replace, if desired, the inking band 44. In the modified construction the platen 5 is depressed circumferentially, as indicated at 60, and at the sides of the depression 60 are formed slightly deeper grooves 61. An inking band or strip 62 is wound one or more times around the depressed surface of the platen at 60 and the side edges of this inking band are fastened in the grooves 61 in any suitable way as by pins 63. It will be noted in Fig. 8 that the heads of these pins 63 are below the printing surface of the inking band 62. It will also be seen that this modified inking band is in fact an endless band which will be turned with the platen when the latter is line spaced. When the exposed surface of the inking band is exhausted, the used portion may be disconnected from the platen and unwound until a fresh portion is exposed, the used portion being cut off and thrown away.

I am aware that it is not new to provide means for automatically line spacing the tally strip; and also that, broadly speaking, an endless inking ribbon is not new. Accordingly it will be found that I do not claim these matters broadly in the accompanying claims but only in combinations which clearly distinguish from the prior art.

Various changes may be made without departing from the spirit of my invention.

What I claim as new and desire to secure by Letters Patent, is:—

1. In a typewriting machine, the combination of a platen, paper feeding devices co-operative therewith to feed a work sheet, a tally strip supporting device, an inking band interposed between the tally strip and said platen, said inking band being independent of said paper feeding devices, means for advancing said tally strip independently of said platen, and means for turning the platen in line spacing direction and thus automatically advancing said inking band independently of the tally strip.

2. In a typewriting machine, the combination of a platen, paper feeding devices co-operative therewith to feed a work sheet, tally strip rolls arranged above said platen and carrying a tally strip which passes from one roll around the platen to the other roll, controlling devices for each of said rolls, an endless inking band extending around the platen and interposed between the platen and the tally strip, said inking band being independent of said paper feeding devices, means for turning the platen and thus automatically advancing the inking band, and separate means for advancing the tally strip.

3. In a typewriting machine, the combination of a platen, paper feeding devices co-operative therewith to feed a work sheet, tally strip rolls arranged above said platen and carrying a tally strip which passes from one roll around the platen to the other roll, controlling devices for said rolls, an endless inking band between said platen and said tally strip, said inking band being independent of said paper feeding devices, said band being supported above the platen and extending from its support around the platen, means for turning the platen and advancing said inking band independently of the tally strip, and means for advancing the tally strip step-by-step.
4. In a typewriting machine, the combination of a platen, line spacing devices therefor, feed rolls co-operating with the platen, means for releasing said feed rolls including a hand-controlled rock shaft, tally strip rolls, and means connected with one of said rolls for line spacing the tally strip, said last named means comprising an arm on said rock shaft, a link connected at one end to said arm, a pivoted arm connected with the other end of said link, and a pawl on said pivoted arm.
5. In a typewriting machine, the combination of a platen, line spacing devices therefor, feed rolls co-operating with the platen, means for releasing said feed rolls including a hand controlled rock shaft, rotary tally strip rolls, and means for line spacing the tally strip, said means comprising an arm on said rock shaft, a second arm pivoted on the axle of the receiving tally strip roll, a link connecting said arms, a spring-pressed
- pawl mounted on said second arm, and a ratchet wheel connected with the receiving tally strip roll and co-operative with said pawl.
6. In a typewriting machine, the combination of a platen carrier, a platen thereon, a bracket secured at one end of said platen carrier and rising therefrom, rods secured to said bracket and extending horizontally inward therefrom over the platen, tally strip rolls rotatably mounted on two of said rods and carrying a tally strip which extends from one roll to the other around the platen, a spool on another of said rods, said spool being arranged between depending unwound portions of the tally strip, an endless inking band extending from said spool around the platen within the unwound portion of the tally strip, means for turning the platen in line spacing direction and advancing the inking band, and separate means for line spacing the tally strip, said separate means including a hand controlled rock shaft, an arm fixed thereon, a second pivotally mounted arm, a link connecting said arms, a pawl on said pivotally mounted arm, and a ratchet wheel co-operative with said pawl and connected with one of said tally strip rolls.

Signed at the borough of Manhattan, city of New York, in the county of New York and State of New York this 21st day of April A. D. 1909.

CLIO B. YAW.
